UNITED STATES PATENT OFFICE.

MILTON W. MAITLAND, OF BORDENTOWN, NEW JERSEY.

DESIGN FOR OIL-CLOTH.

No. 37,566.

Specification for Design.

Patented Sept. 26, 1905.

Application filed November 21, 1904. Serial No. 233,744. Term of patent 3½ years.

To all whom it may concern:

Be it known that I, MILTON W. MAITLAND, a citizen of the United States, residing at Bordentown, in the county of Burlington and State of New Jersey, have invented a new and original Design for Oil-Cloth, as shown in the accompanying drawing, which is a plan view.

I claim—

The ornamental design for oil-cloth, as shown.

MILTON W. MAITLAND.

Witnesses:

W. M. S. GINGLEN,
H. W. KUNZI.
